UNITED STATES PATENT OFFICE

JOSEPH M. TOWNSEND, OF WORCESTER, MASSACHUSETTS

ETCHING MACHINE

Application filed June 1, 1929. Serial No. 367,741.

This invention relates to a machine for etching printing plates in a bath of acid or the like.

The principal objects of the invention are 5 to provide a means for periodically and regularly lifting the printing plate out of the bath and plunging it back into it repeatedly; to provide means for supporting the plate in a horizontal position so that it may be introduced 10 into the bath uniformly over its entire area; to provide means of a simple and convenient character for tipping the plate up out of the bath to be inspected by the operator and to provide for the protection of the 15 machinery from the acid and other fumes of the bath.

Other objects and advantages of the invention will appear hereinafter.

Reference is to be had to the accompanying 20 drawings in which

Fig. 1 is a perspective view showing one embodiment of this invention, and

Fig. 2 is a similar view of another form.

The usual method of applying the acid 25 bath to plates for etching purposes is to spray or splash the liquid over the plate. It is necessary to apply the liquid and then allow the air to get to the plate a plurality of times during the etching operation and one object 30 of this invention is to arrange for this action in a uniform and periodic manner so as to avoid irregular treatment of the plate.

The invention is shown in Fig. 1 as embodied in a machine comprising a base 10 and 35 two uprights 11. Each upright has a horizontal shelf 12, preferably integral with the upright, and on these shelves rests the tank 13 containing the acid to be used.

The plate P is supported from a shaft 14 arranged 40 horizontally. For this purpose the shaft is provided with two supports 15 clamped to the shaft. They are shown as slit longitudinally and provided with a bore for the shaft and a screw 16 for fixing them 45 firmly to it. If desired, a fixed support 17 may be employed secured in the same way on a horizontal rod 18 which in turn is fixed by a clamp 19 to the shaft 14 in a similar way. These supports are provided with notches 20 in the bottom providing a horizontal projec-

tion on which the plate rests and they are adjusted before being clamped so as to apply a slight pressure to the edge of the plate where it engages the slanting side of the notch.

This shaft 14 is supported in open-topped U-shaped yokes 21 which are mounted on the top of two vertical rods 22. These rods slide in bearings 23 on the uprights 11. At the bottom the rods 22 are provided with 55 yokes 24 on which are rollers 25. These rollers rest on and are operated by cams 26 and the yokes straddle a shaft 29. These cams are operated by a motor 27, gearing 28 and the shaft 29 on which they are located.

The shaft 14 is held up against the yokes 21 by collars 30 and on the end it has a handle 31 by which the shaft can be turned. On one of the rods 22 is a segment 32 having two depressions 33. The handle 31 has a 70 knob 34 with a spring plunger which sets into these depressions and holds the handle in either one of the two positions. The shaft 14 therefore can be turned to bring the plate P up into substantially vertical position 75 where the operator at the front can inspect the plate and then it can be turned back to the position shown for operation.

The operation is very simple. The motor being started in any ordinary way the shaft 80 29 will rotate regularly and the rods 22 and the shaft 14 will be raised and lowered periodically. The motion is quite small, just enough to raise the plate P out of the liquid and plunge the lower face of it back into it. 85 It is not intended to submerge the plate in the acid.

In the form shown in Fig. 2 the mechanism is very similar to that shown in Fig. 1 90 but a metallic casing 39 is provided for receiving the motor 27, shaft 29 and other mechanical features of the operating means. This casing is used to protect them from the corrosion due to the acid fumes and the like 95 which come from the bath of the etching liquid. In this case therefore the motor and shaft operate two uprights 42 which are not located near the tank and these uprights carry horizontal arms 43 which can be ad. 100

justed and secured in position by set screws 44.

On the end of each arm is an open bearing 41 for the shaft 14 previously described. This shaft, as in the other case, carries by supports 15 and 17 the plate P which is to be etched on the lower surface. The shaft 14 is provided with an arm 31 and spring push button 34 cooperating with the segment 32 and depressions 33 for the same reason as in the other drawings.

The tank 13 is supported on a base 40 at the proper height with respect to the arms 43. This arrangement is provided to protect the machinery from the fumes as stated. Otherwise it operates the same as the construction shown in Fig. 1.

By this means it will be seen that the treatment of the under side of the plate by the acid is periodically regular and that the acid is allowed to act on the plate the same length of time at each submersion. The bottom of the plate also stays out in the air equal periods each time. The plate is subjected to the acid all over its lower surface every time it goes down and there is no danger of any part of that surface being missed even once during the full treatment of the plate. The plate is lowered into the acid slowly as the shaft 29 is rotated only once or twice per second. The number of operations will be dependent upon the character of the work but where a number of plates that are all alike in character are being treated they can all be introduced into the acid the same number of times so as to get absolutely uniform treatment, not only of each plate, but of any desired number of plates.

Although I have illustrated and described only one form of the invention I am aware of the fact that modifications can be made therein by any person skilled in the art without departing from the scope of the invention as expressed in the claims. Therefore, I do not wish to be limited in this respect but what I do claim is:—

1. In an etching machine, the combination with a pair of uprights having projections on their inner sides and a tank for etching liquid supported on said projections, of a pair of reciprocating rods guided by said uprights, means for reciprocating said rods, a shaft supported by said rods above the tank and supports secured to the shaft for holding a plate to be etched in the tank.

2. In an etching machine, the combination with a tank for etching liquid, of means for supporting said tank, a pair of rods, a horizontal shaft carried by said rods above the tank, a series of supports clamped to the shaft, having means at their lower ends for supporting and holding the plates to be etched down in the tank, a shaft below the tank and cams on said shaft adapted to raise and lower the rods and plate during

each rotation of the shaft for the purpose of plunging the lower face of the plate into the liquid in the tank and withdrawing it therefrom.

3. In an etching machine, the combination 70 of a tank for etching liquid, with a pair of rods, means for vertically reciprocating said rods, a shaft, means connected to move said rods for supporting said shaft above the tank, means clamped to said shaft for holding the plate in the tank and means on said shaft for turning it to move the plate forwardly about the shaft as an axis for the purpose of inspection.

4. In an etching machine, the combination 80 of a tank for etching liquid, with a pair of rods, means for vertically reciprocating said rods, a shaft freely supported by said rods above the tank, means clamped to said shaft for holding the plate at a distance below the shaft in the tank, a segment on one of said rods having depressions at the ends, a handle on said shaft for turning it and a knob on the handle having a plunger adapted to enter either of said depressions and hold 90 the plate in a horizontal position or in a forward position with the surface to be etched in front.

5. In an etching machine, the combination 95 with a tank for the etching liquid, of means for supporting a plate to be etched, means for raising the plate and submerging its lower surface in the liquid, and a casing surrounding the raising mechanism to protect it from the fumes of the etching bath.

6. In an etching machine, the combination 105 with a tank for the etching liquid, of means for supporting the plate to be etched in horizontal position and means for lowering the plate in the liquid and raising it out of the liquid a plurality of times during the etching operation, without changing the position of the surface to be etched from a position parallel with the surface of the liquid, said means comprising reciprocable rods having 110 arms projecting therefrom provided with open topped bearings, a shaft carried by said bearings and means depending from the shaft for supporting in the tank the plate to be etched.

In testimony whereof I have hereunto affixed my signature.

JOSEPH M. TOWNSEND.
